UNITED STATES PATENT OFFICE.

HARRY W. HARDINGE, OF NEW YORK, N. Y.

TUBE-MILL.

1,348,642.

Specification of Letters Patent. Patented Aug. 3, 1920.

Application filed September 12, 1916. Serial No. 119,612.

To all whom it may concern:

Be it known that I, HARRY W. HARDINGE, a citizen of the United States, residing at New York, county and State of New York, 5 have invented certain new and useful Improvements in Tube-Mills, of which the following is a full, clear, and exact description.

In disintegrating ores for concentration 10 or like purposes the particles must, as is well known, be reduced to a certain degree of fineness. These particles are called "fines," and coarser particles that pass out with the fines must be re-ground. My present invention relates to this regrinding, and 15 its object is to provide simple and effective means for use with tubemills and the like by which coarse particles which would otherwise escape may be trapped at the outlet and be carried back to the inlet of the mill and discharged into the same. To this 20 and other ends the invention consists in the novel features and combinations herein-after described.

One form of the invention is illustrated 25 in the accompanying drawing, in which—

Figure 1 is a side view; partly in section, of a conical mill equipped with my invention.

Fig. 2 is a section on line 2—2, looking in the direction of the arrows.

The mill shown is the well known conical mill, comprising a tapered barrel or drum 10 with inlet and outlet trunnions 11 35 and 12, respectively, mounted in suitable bearings 13, 14. The drum is rotated about its longitudinal axis by means of a large gear 15.

In a conical mill the material undergoing 40 disintegration assorts itself according to size, the larger pieces occupying the cylindrical portion and the pieces growing smaller and smaller toward the outlet trunnion. A stream of water is kept flowing 45 through the barrel, and as it issues from the outlet trunnion it carries the fines with it. At the same time more or less material may also escape into the trunnion and be washed out with the fines.

I accordingly provide a trap at the inner 50 end of the outlet trunnion, in which coarse particles may sink. This trap may be formed of a channel iron bent to circular shape with the flanges extending inwardly, 55 and placed inside the trunnion casting, as

shown at 16, Fig. 1. Then if any coarse particles find their way over the innermost flange they will sink while the particles fine enough to float pass on, the outermost flange of the channel iron serving as a dam or 60 baffle to prevent outflow of such coarse particles as might by their momentum be carried on into the trunnion.

For the purpose of taking the collected 65 coarse particles from the trap and returning them to the mill at the inlet end for regrinding, I provide one or more helical conveyer pipes 17. Each pipe has one end opening into the trap, (if more than one pipe are used they are connected to trap 70 equidistantly around the same), and the pipes are bent in helical fashion half-way around the mill and have their other ends inserted into the inlet trunnion 11.

Now as the mill revolves the inlet ends of 75 the conveyer will come successively under the coarse material in the circular trap. Such material falls into the open end of the pipe, and as the mill revolves (in the direction of the arrows) the material is carried 80 along the helical pipe on the principle of the Archimedes screw until it reaches the outlet end of the pipe, and falls into the inlet trunnion. In this way the coarse particles intercepted by the trap or dam are 85 reintroduced into the mill immediately.

The discharge ends of the conveyers are 90 extended into the inlet trunnion so that material passing into the mill will not fall into the conveyers when the open ends thereof are in lower position (as shown in Fig. 1) and to prevent material discharged by one conveyer at the top of the trunnion from falling into the open end of a conveyer below, the discharge ends of the conveyers may be staggered axially as in Fig. 1. To prevent any material fed into the inlet end of the trunnion from finding its way into the discharge orifices of the conveyer tubes the latter are extended into the 100 trunnion, as shown.

It is to be understood that the invention is not limited to the construction herein specifically illustrated but can be embodied in other forms without departure from its 105 spirit.

I claim:

1. A grinding mill comprising in combination a rotatable drum having an inlet and a conical outlet portion, a substantially 110

annular inwardly-extending baffle within said drum adjacent the exit thereof, and a pitched conduit rotatable with said drum and communicating at one end with the interior of said drum adjacent to said baffle on the side toward the exit and connected at its other end to empty into said drum on the other side of said baffle.

2. In a tubemill, in combination, a rotatable drum having an inlet and a conical outlet portion, means comprising a conduit rotatable with said drum for conveying material from the outlet of said drum to the inlet thereof, said conduit being in the form of a spiral of increasing then diminishing radius, and means at the delivery end of the

outlet for causing only the coarser particles to enter said conduit.

3. A grinding mill comprising in combination, a rotatable drum having an inlet 20 and a conical outlet portion, a substantially annular inwardly extending baffle secured within said drum in the path of the material being ground, and means for automatically returning coarse material to said 25 drum for regrinding, said means comprising a conveying conduit rotatable with said drum and connected at its opposite ends to said drum on opposite sides of said baffle.

In testimony whereof I hereunto affix my 30 signature.

HARRY W. HARDINGE.
